FOLDING STOCK FOR SHOULDER ARMS

Herve L. Sedelow, Springfield, Mass., assignor to the United States of America as represented by the Secretary of the Army

Filed July 20, 1964, Ser. No. 384,008

5 Claims. (Cl. 42—72)

(Granted under Title 35, U.S. Code (1952), sec. 266)

The invention described herein may be manufactured and used by or for the Government for governmental purposes without the payment to me of any royalty thereon.

This invention relates to shoulder arms and pertains more particularly to the stocks thereof.

It is one object of this invention to provide for shoulder arms a stock in which the butt section may be folded up to lay along the receiver and thereby reduce the length of the weapon while being carried.

It is a further object of this invention to provide such a folding stock which is distinguished for its strength, for the minimum amount of space required when folded and for the simplicity of its design.

The specific nature of the invention as well as other objects and advantages thereof will clearly appear from a description of a preferred embodiment as shown in the accompanying drawings in which:

FIG. 1 is an elevational view of a rifle with the folding stock of the invention installed thereon;

FIG. 2 is an enlarged, fragmentary top view of the stock shown in its extended position;

FIG. 3 is an enlarged, fragmentary top view showing the stock folded alongside the receiver;

FIG. 4 is an enlarged, fragmentary elevational view showing the hinge arrangements of the stock, with the stock in its extended position;

FIG. 5 is a view similar to FIG. 4 but showing the stock folded;

FIG. 6 is a view taken along line 6—6 of FIG. 4; and FIG. 7 is a view taken along line 7—7 of FIG. 6.

Shown in the figures is a rifle 12 which is provided with a stock 14 having a conventional forward section 16 of wood or plastic, which seats the receiver and part of the barrel, and a folding butt section 18. Butt section 18 is composed of a pair of frames 20, which are hingedly mounted at the front ends to the rear end of forward section 16 by a hinge plate 22, and a butt plate 24 which joins the rear ends of the frames and provides the shoulder support for rifle 12.

Frames 20 include a right-hand frame 26 and a left-hand frame 28 both of which are fabricated from a piece of spring steel bar stock bent to a configuration approximately similar to the silhouette outline of a conventional butt piece. The ends of the bar stock form a pair of pintles 30 which extend linearly toward each other at the front end of the respective frame 20 and are rotationally received by the related one of a pair of vertically disposed and laterally spaced sockets 32 in hinge plate 22. Extending from each of the pintles 30 is an arcuate section 34 which is formed, as noted in FIG. 3, to permit displacement of the frames 20 along opposite sides of forward section 16 by compensating for the distance of the respective socket 32 from the related side of the forward section. Each of the frames 20 is formed so that, when pintles 30 thereof are received by the related one of the sockets 32, the arcuate sections 34 press resiliently against the respective ends of the socket. Provided in each end of each of the sockets 32 is a cam surface 36 formed so as to engageably cooperate with the associated arcuate section 34 for converting the resilient pressure of the arcuate sections to pivotal displacement of the respective frame 20 to its

2

folded position alongside forward section 16 and for holding the frame in the folded position.

Each of the frames 20 also includes a top section 38, a bottom section 40, and a connecting rear section 42. As best shown in FIG. 2, right-hand frame 26 and left-hand frame 28 are each bent inwardly to form in top sections 38 and bottom sections 40 a shallow angle X, the apex of which is located approximately one-fourth the length of the frames from the front ends thereof. Formed in each of the top sections 38, at the apex of angle X therein, is an arcuate discontinuity 44 which is essentially U-shaped in configuration and is arranged to extend outwardly to the right, respective to the long axis of rifle 12 looking forwardly from the rear end thereof, and similarly formed in each of the bottom sections 40 is an arcuate discontinuity 46 which extends outwardly to the left.

Thus, when frames 20 are in their extended positions, arcuate discontinuity 44 in top section 38 of left-hand frame 28 nests in the mating discontinuity in the top section of right-hand frame 26, and arcuate discontinuity 46 in bottom section 40 of the right-hand frame nests in the mating discontinuity in the bottom section of the left-hand frame. Arcuate discontinuities 44 and 46 serve to strengthen frames 20 against buckling under recoil forces by dividing the lengths of the frames into shorter linear sections and, when the related discontinuities are pressed together, as hereinafter described, the frictional contact and the nesting engagement which prevents relative movement therebetween serve to form the frames into an essentially X-shaped structure so that the frames are rigidly held against pivotal displacement.

The rear ends of frames 20 are held together by butt plate 24 which is pivotally mounted on rear section 42 of right-hand frame 26 at 48 and is engageable with the rear section of left-hand frame 28 by a spring catch 50. The value of angle X is such that, when discontinuities 44 and 46 are in contact, the rear ends of the frames are normally spaced apart farther than the reach of butt plate 24 so that the rear ends have to be pulled resiliently together and thereby apply pressure between the discontinuities in order for spring catch 50 to engage left-hand frame 28.

A vertical rod 52 is provided in right-hand frame 26 for engagement by spring catch 50, when butt plate 24 is folded alongside the right-hand frame to hold the butt plate against displacement when the frame is folded, and a releasable bracket 54 may be added, as shown in FIG. 2, to assure that discontinuities 44 and 46 are securely held in contact.

Thus, while rifle 12 is being carried and it is more convenient to have the length thereof reduced as much as possible, butt section 18 is folded with frames 20 swung forwardly along opposite sides of forward section 16 with the bias of the arcuate sections 34 against the corresponding cam surfaces 36 holding the frames in their folded positions. When rifle 12 is to be used, frames 20 are swung rearwardly to their extended positions and the ends of the frames are pressed together to where spring catch 50 of butt plate 24 can engage rear section 42 of left-hand frame 28 for securing the frames together.

From the foregoing it is clearly apparent that there is provided herein a folding stock which is simple in design but strong in construction, which may be easily and quickly folded and extended and which increases the bulk of the rifle very slightly when folded.

Although a particular embodiment of the invention has been described in detail herein, it is evident that many variations may be devised within the spirit and scope thereof and the following claims are intended to include such variations.

I claim:

1. A stock for a shoulder arm having a receiver and a barrel, the stock including a forward section for seating the receiver and part of the barrel, and a butt section comprising a pair of frames hingedly mounted on the rear end of said forward section for pivotal displacement between forward folded positions along opposite sides of said forward section and rearward extended positions, a butt plate for joining the rear ends of said frames together when in the extended positions and provide shoulder support for the shoulder arm, and discontinuity means formed in said frames for strengthening and for pressed engagement to hold said frames against pivotal displacement when joined in the extended positions by said butt plate.

2. The stock as defined in claim 1 wherein said discontinuities are arcuately formed in a substantially U-shaped configuration and are so disposed in cooperation that said discontinuities in one of said frames nest in said discontinuities in the other one of said frames when said frames are in the extended positions.

3. The stock as defined in claim 2 wherein said frames are each provided with a rear section and each of said frames is bent inwardly to form an angle at said discontinuities therein, said angle being formed so that said rear ends are normally spaced a distance greater than the

reach of said butt plate when said frames are in the extended positions.

4. The stock as defined in claim 3 wherein each of said frames is provided with a top section and a bottom section joined thereto by said rear section, wherein one of said discontinuities is formed in each of said top sections and bottom sections along the lengths thereof, and wherein said discontinuities in said top sections extend outwardly in one direction and said discontinuities in said bottom section extend outwardly in the opposite direction when said frames are in the extended positions.

5. The stock as defined in claim 3 including means for hingedly mounting said butt plate on said rear section of one of said frames, and a spring catch mounted on said butt plate for engagement with said rear section of the other one of said frames when said frames are in the extended positions.
